J. P. SEAHOLM

PLOW

Filed March 11, 1927

Inventor:

John P. Seaholm

By Reiter, Hitler, Davis, Macaulay Atty's.

UNITED STATES PATENT OFFICE.

JOHN P. SEAHOLM, OF MOLINE, ILLINOIS, ASSIGNOR TO MOLINE IMPLEMENT COMPANY, OF MOLINE, ILLINOIS, A CORPORATION OF ILLINOIS.

PLOW.

Application filed March 11, 1927. Serial No. 174,448.

This invention relates to a plow, particularly to a plow of the type known as a walking plow because the operator walks behind the plow when using it. The invention concerns a simplified construction of this type of plow which departs from the standard practice and enables an efficient plow to be more inexpensively made than has heretofore been the case.

10 The present practice in the manufacture of mold board plows is to provide them with shares that may be removed for sharpening or replacement. These shares not only form an extension of the lower part of the mold board but they have pieces welded onto one end and edge to form a plowing point and a portion of the landside of the plow. The manner in which these shares are constructed and attached to the body of the plow is illustrated in the patent to Esping, No. 1,203,104, October 31, 1916, as well as in many other patents of a similar nature in the prior art. This construction of plow share with a projecting and thickened plowing point and with a landside portion has become so universal that it is accepted as standard practice by all implement manufacturers. The plowing point and the landside portion are made by welding a piece 20 of steel onto the main body of the share which is also usually made of steel. This requires a number of operations and is a relatively expensive process.

25 The present invention contemplates a departure from the standard practice and the provision of a simpler and more inexpensive construction. Instead of providing the share with a welded plowing point and a landside portion, the share is made as a flat metal plate which can be sheared to proper shape from bar stock. The share does not form any part of the landside of the plow. Instead the landside is formed of a flat metal plate which abuts the share and the mold board. The plow is otherwise simplified in its construction so that it may be made inexpensively out of a minimum number of parts.

30 The general object of the invention is to provide an improved and simplified plow.

A more particular object is to provide an improved plow construction in which the share used can be made of a flat metal plate that can be sheared or stamped to shape.

35 Another object is to provide a plow having

its parts so shaped and connected that a minimum number of pieces may be employed in building it.

Other objects and advantages of the invention will appear from the specification and drawings.

An embodiment of the invention is illustrated in the accompanying drawings in which,

Figure 1 is a perspective view of the plow from the front side thereof.

Fig. 2 is a perspective view of the plow from the rear thereof.

Fig. 3 is an enlarged perspective of the plow looking at the bottom thereof.

Fig. 4 is a perspective view of one of the plow shares.

The plow is provided with a plow beam 1, preferably made of a rectangular steel bar bent downwardly at its rear end and provided with a plate 2 at its forward end to which a clevis 3 may be connected. The shape and size of the beam may be varied to suit the requirements but it is made as light as possible consistent with the work to be done.

A landside 4 is connected at its center to the lower rear end of the plow beam by the bolt 5. This landside comprises a flat metal plate having a sloping front edge 6. It will be observed that this plate can be easily sheared or stamped out of flat metal stock without requiring any complicated operations in its manufacture.

A mold board 7 is provided which is supported by a brace 8 to which it is connected by a bolt 9. This brace is a single member cut out of bar stock and bent to proper shape. It is bolted to the plow beam by the bolt 10 and its lower end is connected to the landside 4 by a bolt 11 which also holds a shoe 12 in place which will be hereinafter described. This brace also forms a supporting connection for the handles 13 and 14, one of which is connected to the brace by the bolt 15 and the other to one end of the brace by the bolt 16. This one-piece brace thus forms the function of supporting the mold board, the landside, and the handles, as well as acting as a connecting means for connecting the parts together and making them rigid.

The handles 13 and 14 have braces 17 and 18 respectively extending forward and connected at the point 19 to the plow beam.

- Connected to the rear side of the mold board near its lower end is a supporting plate 20 having an angle portion 22 connected to the landside 4 by the bolt 23. This plate is connected to the mold board by the bolts 24 and 25, the latter also serving to connect one end of an angle brace 26 in place, the other end being held in position by the same bolt 5 which connects the plow beam 1 to the landside 4. This structure serves to rigidly brace the lower portion of the plow and it also forms a support for the plow share.

The plow share 27 comprises a flat metal plate having a sharpened edge 28 and an end edge 29 which forms an acute angle with the sharpened edge and provides a plowing point 30. The share has holes 31 and 32 in it for the reception of bolts 33 and 34 by means of which it is connected to the supporting plate 20. When bolted in position the share rests against the supporting plate 20 and abuts against and is supported by the sloping edge of the landside 4. It will be noted that this share can be quickly and easily made out of flat metal stock by simply cutting or shearing off the required length for the share.

The landside 4 is preferably positioned slightly inward from the land edge of the plow share 27 and the mold board 7 as illustrated in Fig. 2. It is also positioned slightly above the lower edge 28 of the share. This gives a slight clearance for the point of the plow share as shown most clearly in Fig. 3. Positioned on the outside and beneath the lower edge of the landside at its rear end is an L-shaped shoe 12 which is held in place by the main bolt 11 that holds the brace 8 to the landside. The outside surface of this shoe is substantially in line with the land edge of the share and the mold board and the lower side of the shoe is substantially in line with the lower surface of the share. Its front edges are sloped toward the landside to avoid forming abrupt edges which might hinder the smooth operation of the plow. This shoe takes the wear off the landside and forms a small inexpensive part that may be easily replaced.

From the description and illustration given it will be readily apparent that a simplified form of plow has been developed which can not only be inexpensively manufactured in the first place but which is constructed so that the shares that need replacement from time to time can be most inexpensively made. All of the parts can be made out of flat metal stock by a few simple operations and the plows constructed so that a minimum number of these parts are employed. By avoiding the expensive operations of welding a landside and a plowing point on the plow share the cost of these shares is greatly reduced and a

farmer may replace his shares at such small cost that it will not pay him to have them sharpened.

It is to be understood that the structure shown is for purposes of illustration and that modifications may be made in it without departing from the spirit and scope of the invention as defined by the claims.

I claim—

1. A detachable share for plows comprising a plain metal plate free of projections and openings except the openings for receiving bolts to hold the share in place, said share being flat and of substantially uniform thickness throughout, one of the side edges of the plate being beveled and one of the end edges being at right angles to the side edges, the other end edge being at an acute angle to the beveled edge. 75

2. The combination with a plow having a curved metal mold board, of an independent landside member, a supporting plate, and a detachable share bolted to the supporting plate, said share comprising a metal plate flat and of substantially uniform thickness 80 throughout its entire length, the upper edge of the share being abutted against the lower edge of the mold board and the lower side edge being beveled, the furrow end edge of said plate being at an acute angle to the lower edge to form a plow point. 85

3. The combination with a plow having a curved metal mold board, of an independent land side member having a front sloping edge substantially in line with the rear surface of the mold board, a supporting plate, and a detachable share bolted to the supporting plate, said share comprising a metal plate flat and of substantially uniform thickness 90 throughout with its upper edge abutting the lower edge of the mold board, and its lower edge beveled, the furrow end edge of said plate being at an acute angle to the lower edge and the furrow end of the share being supported by the sloping edge of the 105 landside. 110

4. A plow having a mold board, a share, a landside positioned slightly inward from the land edge of the mold board and share, and a shoe on the outside of the landside 115 near the rear thereof with its surface substantially in line with the land edge of the mold board and share.

5. A plow having a mold board, a share, a landside positioned slightly inward from the land edge of the mold board and share and slightly above the lower plowing edge of the share, and a shoe positioned on the outside and under the lower edge of the landside near the rear thereof. 120

6. A plow having a mold board, a landside, a supporting plate connected to the landside and mold board, a share comprising a flat metal plate detachably connected to the supporting plate and supported at one end by 125 130

the landside, a brace connected to the supporting plate by a bolt that also holds the plate to the mold board, a plow beam connected to the landside near the center thereof by a bolt which also holds the brace, a shoe for the rear of the landside, and a brace connected to the landside by a bolt which also

holds the shoe in place, said brace being connected to the plow beam and to the mold board and having portions to which plow **10** handles are connected.

In testimony whereof, I have subscribed my name.

JOHN P. SEAHOLM.
